His Attorney.

UNITED STATES PATENT OFFICE

2,221,684

ELASTIC FLUID TURBINE BUCKET WHEEL

Arthur R. Smith, Schenectady, N. Y., assignor to
General Electric Company, a corporation of New
York

Application August 27, 1938, Serial No. 227,151

6 Claims. (Cl. 253—77)

The present invention relates to elastic fluid turbine bucket wheels and more particularly to arrangements for covering and tying together the outer ends of the buckets.

5 In turbine bucket wheel construction, adjacent buckets or blades are usually connected together by some form of a cover or shroud band attached to the ends of the buckets to confine the operating fluid within the working passage 10 and to prevent it from spilling outwardly past the ends. Because of the relatively great tangential force exerted by the operating fluid against the buckets, particularly in the high pressure stages, a certain amount of bending of the 15 individual buckets takes place which is accompanied by a corresponding distortion of the cover between adjacent buckets. This distortion of the cover together with the centrifugal force due to the wheel rotation, acting outwardly thereon, 20 and the force exerted by the operating fluid acting directly against the surface of the cover severely stresses the attaching means as well as the cover itself. In elastic fluid turbines designed not only for high speed operation but also 25 for modern high pressures and temperatures, the stresses due to the combined forces acting upon the cover are greatly amplified. The usual form of cover consisting of a single tie member has proved incapable of withstanding such stresses as are imposed upon it during severe operating 30 conditions.

It is an object of this invention to provide a new and improved turbine bucket wheel shrouding arrangement of greatly increased strength that is capable of withstanding extreme operating 35 conditions.

It is a further object of this invention to produce a new and improved turbine bucket wheel shrouding arrangement by which the stresses are distributed to the adjacent buckets on both sides of the one being acted upon by the operating fluid 40 while the tying member is secured throughout its length against distortions likely to cause fatigue and failure thereof.

45 For a consideration of what I believe to be novel and my invention, attention is directed to the following description and the claims appended thereto taken in connection with the accompanying drawing.

50 In the drawing, Fig. 1 represents a section of a turbine bucket wheel in perspective provided with a cover according to my invention, Fig. 2 is a fragmentary elevation illustrating the manner in which the cover shown in Fig. 1 is assembled, while Figs. 3 and 4 illustrate a second 55 modification of the invention.

Referring to Fig. 1 of the drawing, 10 indicates the web of the wheel disk or rotor and 11 the grooved rim thereof which on opposite sides is 60 provided with annular shoulders defining a dove-

tailed portion 12 for retaining the buckets or blades 13 thereon. The bucket bases 14 are provided with a grooved slot defining an inverted dovetail for cooperatively fitting over the rim of the rotor substantially as shown. This bucket fastening means forms what is commonly termed the inverted dovetail type of fastening and in itself is well known in the art and typical of bucket wheels in connection with which my present invention may be carried out. It is understood, of course, that the buckets may be secured to the rotor in any other suitable manner.

10 According to my invention, the buckets or blades 13 are each provided with relatively rigid cover portions 15 substantially bridging the space 15 between adjacent buckets at the outer ends thereof. These cover portions prevent the operating fluid from escaping upwardly past the ends of the buckets and absorb the force which would otherwise be directed against the shroud band 20 or tying means. It is preferred that the cover portions are formed integrally with the buckets and be so dimensioned that the facing surfaces of adjacent covers substantially abut with each other around the periphery of the wheel to maintain a proper spacing of the bucket ends.

25 Means are also provided for connecting or tying 30 a group of any suitable number of adjacent buckets together. The outer surface of each cover portion is provided with a circumferentially extending undercut slot 16 so located that it aligns with the adjacent ends of the slots formed in the adjacent covers whereby a continuous circumferential slot is formed adapted to receive the tying means 17.

35 The opposite side walls 18 of the slot are provided with overhanging portions or beads 19. An integral raised portion or lug 20 centrally disposed within the slot of each bucket cover extends upwardly from the base thereof. The tying means 17 comprises a pair 40 of similar metal straps or bars 22 which are provided with aligned notches 23 along their adjoining edges for cooperatively fitting around the lugs 20 when they are assembled within the slot 16.

45 As shown more clearly in Fig. 2, the straps may be separately assembled into the slot 16 by first inserting the outer edges thereof under the overhanging beads 19 as shown at the left in Fig. 2 and then shifting them so that they lie flat against the base of the slot as shown at the right. After both straps have been assembled in position, they may be secured in place by peening over the edges of the centrally disposed lugs 20. The straps 22 will thereby be forced outwardly 50 against the side walls 18 of the slot. The beads 19 may then be rolled or peened over to securely clamp the outer edges of both straps in place substantially throughout their entire length. The lugs 20 and the notches 23 are substantially 55 rectangular in shape so as to minimize any wedg- 60

ing apart of the straps when they are tensioned. As shown, groups of four buckets are tied together, though it is obvious that any suitable number may be grouped together as desired.

- 5 Since the tying straps 22 are rigidly clamped against the base of the circumferential slot along the adjoining inner edges by means of the peened lugs 20 and along the outer edges by the beads 19, it is seen that the outer ends of the buckets are 10 rigidly secured together against relative movements therebetween. Such relative movements can take place only if relative sliding movements are permitted between the abutting faces of the integral cover portions. Such sliding movements 15 are resisted by the shear strength of the straps 22 fixedly clamped against the surface of the cover portions in the slot 16 as described. By virtue of the integral cover portions 15, the bucket tying means is not directly stressed by the pressure 20 of the operating fluid passing through the working passage. Since the tying means is secured against undue stressing and distortion, the possibilities of failure thereof from fatigue are minimized.
- 25 In Figs. 3 and 4 is shown a second modification of the invention in which the slot side walls are substantially smooth and perpendicular with respect to the slot base. A single piece tying member or strap 25 may thus be used for tying together a predetermined number of buckets. The strap is suitably perforated for fitting over the lugs 26, which are adapted to be peened, as shown in Fig. 4, to secure the straps in place. The strap is secured against distortions or bending 30 by peening or rolling the extended edges 27 of the slot side walls over the outer edges of the strap substantially as shown in Fig. 4. By beveling the edges of the strap as at 28, a considerable thickness of metal may be rolled over the tying member to amply resist the shearing stresses between adjacent buckets.

Having described the principle of operation of my invention together with the apparatus which I now consider to represent the best embodiment thereof, I desire to have it understood that the apparatus shown is only illustrative and that the invention may be carried out by other means.

What I claim as new and desire to secure by Letters Patent of the United States, is:

- 50 1. In an elastic fluid turbine having a rotor with buckets mounted on the rim thereof, said buckets being provided with integral cover portions, aligned slots provided in the upper surface of said cover portions, integral portions extending upwardly from the base of said slot of each of said cover portions and spaced from the side walls thereof, means for tying a plurality of adjacent buckets together comprising a pair of bands fitted into said slot on opposite sides of 55 said integral portions, the edges of said side walls and said integral portions peened over the edges of said bands to secure said pair in said slots.
- 60 2. In an elastic fluid turbine having a rotor with buckets mounted on the rim thereof, said buckets being provided with individual cover portions integral with the outer ends thereof, a slot provided in the upper surface of each of said cover portions, the slots of adjacent buckets being so aligned as to provide a continuous circumferential slot around the periphery of said buckets, a centrally disposed lug extending upwardly from the base of said slot in each of said cover portions and spaced from the side walls thereof, means for tying a plurality of adjacent buckets 65

together fitted into said slot and perforated to cooperatively fit around said lugs, the upper edges of said lugs being deformed to securely fasten said tying means in said slot.

3. In an elastic fluid turbine having a rotor 5 with a row of buckets mounted on the periphery thereof, said buckets being provided with integral cover portions, the cover portions of adjacent buckets substantially abutting against each other and spacing the outer ends of said buckets apart, 10 means for securing a plurality of adjacent buckets together comprising integral lug portions centrally disposed and projecting upwardly from each of said cover portions, tying means provided with spaced apart perforations for cooperatively 15 fitting around said lugs, the edges of said lugs being peened over said tying means, and means for securing the outer edges of said tying means against the surface of said cover portions.

4. In an elastic fluid turbine having a rotor, 20 buckets secured to the rim of said rotor, each of said buckets having a cover portion rigidly connected to the outer end, the cover portions of adjacent buckets abutting with each other to space said buckets apart, the upper surface of 25 said covers being slotted so as to provide a continuous circumferential slot around said buckets, a rectangular lug projecting upwardly from the base of said slot and centrally disposed in each cover portion with respect to the side walls of 30 said slot, means for securing a plurality of said buckets together comprising a member perforated so as to cooperatively fit around said lugs and secured in said slot by the peened over edges of said lug, the edges of said side walls being peened 35 over the outer edges of said tying member.

5. In an elastic fluid turbine, a rotor having a row of buckets mounted thereon, each of said buckets having an integral cover portion, the cover portions of adjacent buckets substantially 40 abutting against each other and spacing the outer ends of said buckets apart, a slot in the upper surface of each of said cover portions, the slots being so aligned as to form a continuous circumferential slot around the periphery of said 45 row of buckets, the side walls of said slots having overhanging beads, rectangular lugs integral with said cover portions extending upwardly from the bottom of said slot and centrally disposed therein with respect to said side walls, a pair of tying 50 members for securing a plurality of adjacent bucket covers together, said tying members each being perforated along one edge for cooperatively fitting around said rectangular lugs, the other edge of each of said tie members adapted to cooperatively fit under the overhanging bead of 55 said side wall, said tying members being secured in said slot against the base thereof by peened over edges of said lugs and said overhanging beads.

6. An elastic fluid turbine bucket having an individual cover portion integral with the upper end thereof, a slot provided in the upper surface of said cover portion adapted to receive a member for tying a plurality of similar buckets together, the upper edges of the slot side walls being provided with overhanging beads, a centrally disposed lug extending upwardly from the base of said slot and spaced from the opposite side walls thereof, the overhanging beads and the upper edges of said lug adapted to be deformed to rigidly secure a tying member against the base of said slot.

ARTHUR R. SMITH.
